erty Custodian

No Drawing. Application October 1, 1940, Serial
No. 359,231. In Germany October 4, 1939

1 Claim. (Cl. 196—53)

The present invention relates to a process for the production of motor fuels.

It is known that hydrocarbon mixtures containing naphthenic hydrocarbons and boiling mainly within the boiling range of middle oils, i. e., between about 200° and about 325° C., can be converted into low-boiling hydrocarbon oils of the gasoline type by cracking them at a temperature above 400° C. in the presence of stationary catalysts. In this process, however, the catalyst loses efficiency already after a short use, owing to the deposition of high molecular weight polymerization products to such an extent that it must be reactivated or regenerated by the removal of these products. An excessive formation of undesirable deposits upon the catalyst can only be avoided by performing the reactivation of the catalyst after a short use for the desired reaction. It was only by the development of the catalytic destructive hydrogenation in the gas phase that it has become possible to convert middle oils into gasolines practically without the catalysts suffering a decrease of activity. Unlike the ordinary catalytic cracking process, however, the destructive hydrogenation must be carried out in apparatus capable of withstanding high pressures; besides, since hydrogen is consumed in the reaction, means for its production must be provided.

We have now found that naphthenic hydrocarbon mixtures substantially of the middle oil boiling range can be cracked under such reaction conditions that, though hydrogen is present, there is no net consumption thereof, that high pressure is not needed, that the catalyst remains active for remarkably long periods of time and that gaseous hydrocarbons are formed to a comparatively slight extent only. For this purpose, the initial materials, while in a vaporous state, are passed over one or more of the oxides of the metals of the 2nd to the 6th group of the periodic system, at temperatures between 440° and 550° C., together with hydrogen, under a total pressure between about 25 and about 90 atmospheres and a partial pressure of hydrogen which amounts to from about 30 to about 50 per cent of the total pressure and lies below 30, preferably below 20 atmospheres, and the gases containing hydrogen leaving the reaction space are returned thereto, without adding fresh hydrogen, if desired after enriching their content in hydrogen, in an amount of from 0.3 to 1.5 cubic meters per kilogram of initial material.

As initial materials may be mentioned hydrocarbon mixtures, approximately of the middle

oil boiling range, which contain at least 35 per cent of naphthenes, as well as fractions thereof. They may be obtained from naphthenic or asphalt-base mineral oils or from destructive hydrogenation products of mineral oils, tars or coals. The specific gravity of the fractions boiling from about 290° to about 310° C. or from about 250° to about 270° C., contained in the initial materials, advantageously amounts to more than 0.85 and 0.83, respectively.

As catalysts may be used, for example, the oxides of chromium, molybdenum or vanadium or mixtures thereof, as for example mixtures of oxides of chromium and vanadium, which are deposited on carriers, as for example active silica, bleaching earth, kieselguhr, magnesia or zinc oxide and preferably on active alumina. Natural or artificial aluminum and/or magnesium silicates, which may be provided with a metal oxide, especially one of those cited above, may also be employed.

The total pressure preferably ranges between about 30 and about 65 atmospheres, especially between 40 and 60 atmospheres.

The gases containing hydrogen leaving the reaction chamber are returned advantageously in an amount of 0.5 to 1 cubic meter per kilogram of the initial material. Fresh hydrogen is only supplied at the outset of the process. During the operation an addition of hydrogen is not required, since no hydrogen is consumed and the quantity returned will suffice to prolong the activity of the catalyst. If any excessive amounts of undesired gases, especially gaseous hydrocarbons, as for example methane, should accumulate in the hydrogen to be returned, they may be removed wholly or in part, for example by washing. For this purpose, a partial current of the gases leaving the reaction chamber may be branched off and purified and the resulting hydrogen returned to the reaction chamber either alone or together with unpurified gas.

The reactivation of the catalyst cannot, indeed, be entirely dispensed with, but the periods of operation are considerably longer than when working without hydrogen. They are at least two hours, in general from 4 to 20 hours, and may even be considerably longer, say several days. It may be of advantage to pass the gas containing hydrogen returned alone, i. e., without initial material, over the catalyst, at intervals, for some time at the reaction temperature, whereby the catalyst is partly reactivated and the necessity of a complete reactivation is put off.

The reactivation is accomplished in known

manner by means of gases containing oxygen, the percentage of oxygen in the gas being preferably low initially and increased gradually, at an elevated temperature and, if desired, under pressure. The catalysts mentioned above may be reactivated many times.

The products obtained by a single pass through the reaction chamber consist to the extent of about 25 to 40 per cent of gasoline and of an aromatic middle oil. According to the choice of the conditions the yield of gasoline may be increased or diminished. The resulting gasoline is a non-knocking motor fuel. The aromatic middle oil may be returned to the reaction chamber or converted into non-knocking motor fuels by any other suitable method, as for example a destructive hydrogenation.

The following example serves to illustrate how the present invention may be carried out in practice, but the invention is not restricted to this example.

Example

A naphthenic middle oil (boiling range 200° to 325° C.; specific gravity 0.860; aniline point 40° C.) is passed over a catalyst consisting of active alumina with 13 per cent of chromium oxide under a total pressure of 50 atmospheres and a hydrogen partial pressure of about 18 atmospheres at a temperature of 505° C. The gaseous reaction products obtained which contain 43 per cent of hydrogen are returned to the reaction chamber in an amount of 0.6 cubic meter per kilogram of initial material. The chamber is filled with pieces of catalyst which are slowly

passed therethrough. The catalyst remains in the reaction chamber for about 8 hours.

Besides 13.5 per cent of gases, a liquid product is obtained which consists of 27 per cent of gasoline and 73 per cent of middle oil. The middle oil is low in hydrogen and of aromatic nature; the gasoline contains 32 per cent of constituents boiling up to 100° C., possesses an octane number of 82 and a content of olefines amounting to 1.5 per cent.

What we claim is:

In a process for the production of knock-resistant motor fuels from hydrocarbon oils by catalytic vapor phase cracking at elevated temperatures and pressures in the presence of hydrogen and recycling of hydrogen-containing reacted gases, the improvement which comprises using in combination a naphthenic starting material boiling mainly within the boiling range of middle oils, an oxide 15 of a metal selected from the 2nd to the 6th group of the periodic system as the catalyst, a temperature of 440-550° C., a total pressure of 25-90 atmospheres, a hydrogen partial pressure of less than 30 atmospheres and amounting to 30-50% of the total pressure and a gas recycle ratio 20 of 0.3-1.5 cubic meters per kilogram of starting material, partly reactivating the catalyst by passing the hydrogen-containing recycle gas over the catalyst at the cracking temperature without the 25 addition of initial material and completely reactivating the catalyst after a reaction time of at least two hours.
